UNITED STATES PATENT OFFICE

RAY P. ROSENBERRY, OF CLEVELAND, OHIO, ASSIGNOR TO THE SILVER KING HYDRAULIC JACK COMPANY, OF CLEVELAND, OHIO, A CORPORATION OF OHIO

HYDRAULIC JACK

Application filed April 7, 1930. Serial No. 442,116.

This invention relates to hydraulic jacks, and has for its principal object the provision of an improved jack of this type. In the drawings accompanying this specification, and forming part of this application, I have shown, for purposes of illustration, one form which my invention may assume, and in these drawings:

Figure 1 is a side elevational view of one embodiment of the invention, a portion of the operating handle being broken away,

Figure 2 is a horizontal sectional view corresponding substantially to the line 2-2 of Figure 1,

Figure 3 is a vertical sectional view corresponding substantially to the line 3-3 of Figure 2,

Figure 4 is an enlarged vertical sectional view of the upper end of the ram cylinder, reservoir casing, and ram, while

Figure 5 is an enlarged vertical sectional view corresponding to the line 5-5 of Figure 1.

In the embodiment of the invention set forth in the drawings, the jack is provided with a base 10, from which rises a reservoir casing 11 and a ram cylinder 12. The reservoir casing 11 and ram cylinder 12 are cast integrally, in substantially elongated oval conformation in cross-section, with a straight transverse dividing wall 13 therebetween. The reservoir casing 11 and ram cylinder 12 are also cast integrally with the base 10, and the casting is strengthened by the provision of longitudinally disposed webs 14 extending between the adjacent walls of the reservoir casing 11, the ram cylinder 12, and the curved flanges 15 at opposite ends of the base 10.

Cast integrally with the base 10 and the side wall 16 of the reservoir casing 11 and ram cylinder 12, is a laterally disposed extension 17 having transverse bores 18 and 19, the bore 19 communicating with the ram cylinder 12, as indicated at 20, and being closed at its outer end by a threaded plug 21, and the bore 18 communicating with the reservoir casing 11, as indicated at 22, and having its outer end closed by a threaded plug 23. A bore 24 extends longitudinally

of the casting, and intersects bores 18 and 19, the outer end of the bore 24 being closed by a threaded plug 25. Between the bores 18 and 19, the bore 24 is provided with a valve seat 26, cooperating with a ball valve 27, yieldably held to its seat by a spring 28. The inner end of the bore 18 also is provided with a valve seat 29, cooperating with a ball valve 30, yieldably held to its seat by a spring 31. The bore 18 communicates through a bore 32 with a pump cylinder 33, formed in a vertically extending portion 34 of the extension 17. The pump cylinder 33 has mounted therein a reciprocable plunger 35, extending upwardly through a stuffing box 36, and at its outer end pivotally connected at 38 with a lever 37 pivotally connected at 39 with a link 40 pivotally secured to a fixed stud 41. The opposite end of the lever 37 is provided with a pair of transversely extending pins 42 adapted to accommodate one end of a handle 43, the handle having bayonet slots 44 for receiving the pins 42.

The stuffing box 36, best shown in Figure 5, has means for returning leakage to the reservoir casing 11. This means comprises an enlarged cylindrical portion 45, having counter bores 46 and 47, the latter communicating with the plunger cylinder 33, and having its bottom defining walls 48 tapered. Mounted in the counter bore 47 is a sleeve-like packing member 49, having a cylindrical portion 50 with the lower end 51 beveled or inclined having also a laterally extending flange 52 seated upon the shoulder 53. Disposed above the flange 52 of the packing member 49 is a washer 54 having in its periphery a circumferential groove 55 communicating through a transverse bore 56 with the space adjacent the plunger 35. The groove 55 also communicates with the reservoir by means of a duct 57 opening through the wall of the casting into the interior of the reservoir 11, and any liquid escaping past the packing member 49 will be returned to the reservoir 11 by way of the bore 56, groove 55, and duct 57.

Loosely mounted in the cylinder member 12, for reciprocation therin, is a cylindrical

return of the liquid in the cylinder 12 to the reservoir 11, the valve 86 of course being again closed prior to a subsequent elevating operation of the jack.

From the above description it will be obvious to those skilled in the art that the invention provides a new and improved hydraulic jack. At the same time those skilled in the art will appreciate that the embodiment of my invention herein shown and described may be used for other purposes than those specifically pointed out or suggested, and embodies advantages and uses other than those specifically pointed out or suggested herein, and also that this particular embodiment of my invention herein described may be variously changed and modified, without departing from the spirit of my invention or sacrificing the advantages thereof, wherefore it will be understood that the disclosure herein is illustrative only, and that my invention is not limited thereto.

I claim:

1. A hydraulic jack having a ram cylinder and a reservoir disposed in line and having a flat dividing wall common to both cylinder and reservoir, said cylinder having an unfinished inner surface; a closure for the upper portion of said ram cylinder; a cylindrical ram mounted in said ram cylinder and extending through said closure, said ram being disposed throughout its length in spaced relation with the walls of said cylinder; and means for withdrawing fluid from said reservoir and forcing the same into said ram cylinder entirely around said ram, for elevating said ram by displacement.

2. A hydraulic jack having a ram cylinder and a reservoir disposed in line and cast integrally with a flat dividing wall common to both said cylinder and said reservoir, said cylinder having an unfinished inner surface; said dividing wall having a valve port opening therethrough for establishing communication between said ram cylinder and said reservoir; a closure for the upper portion of said ram cylinder; a ram mounted in said ram cylinder and extending through said closure, said ram being disposed throughout its length in spaced relation with the walls of said cylinder; means for withdrawing fluid from said reservoir and forcing the same into said ram cylinder entirely around said ram, for elevating said ram by displacement; and a valve extending through said reservoir, substantially at right angles to said dividing wall and operable to open and close the port in said wall to control communication between said ram cylinder and said reservoir.

In testimony whereof I hereunto affix my signature.

RAY P. ROSENBERRY.
